FRANCIS J. WEBER, OF CAREY, OHIO.

Letters Patent No. 69,286, dated September 24, 1867.

IMPROVEMENT IN MACHINES FOR MAKING WAGON-WHEELS.

The Schedule referred to in these Letters Patent and making part of the same.

TO ALL WHOM IT MAY CONCERN:

Be it known that I, FRANCIS J. WEBER, of Carey, in the county of Wyandotte, and State of Ohio, have invented a Self-Centring-Hub Mandrel and Set-Staff; and I do hereby declare the following to be a full, clear, and exact description thereof, reference being had to the accompanying drawings, in which—

Figure 1 is a perspective view of a hub having one spoke inserted into it showing my improved device applied and ready for use.

Figure 2 is a sectional view of fig. 1.

Figure 3 is a sectional view of the staff and its key-rod for holding the gauge.

Similar letters of reference indicate corresponding parts in the several figures.

Similar letters of reference indicate corresponding parts in the several views. This invention relates to a new and improved contrivance which is designed for use in setting spokes into the hubs of wheels, for the purpose of having all the spokes inserted at the proper angle or "dish." It consists mainly in a centring device which is adapted for finding the exact centre of the hole through a hub, and also for serving as a pivot for a revolving staff which carries the gauge by which the dish of the wheel is fixed, as will be hereinafter described. It also consists in so constructing the centring device that it shall serve as a means for centring and supporting the gauge-staff, and also for attaching this staff to a hub so that the gauge will sweep around in the path of a circle which is concentric to the axis of the hub, as will be hereinafter described. It also consists in a novel device for securing the gauge, by which the dish of the spokes is fixed to its staff at different distances from the centre of the hub, and also at different distances from a plane intersecting the centres of the mortises in the hub, as will be hereinafter described.

To enable others skilled in the art to understand my invention, I will describe its construction and operation.

In the accompanying drawings, A represents the hub of a wheel, which is bored out and mortised ready for receiving the spokes. B represents one spoke inserted into the hub A, ready for being adjusted and set to the proper dish or angle. Through the bore A' of the hub A I insert a rod, a, having upon it a cone, c, which abuts against a shoulder, a', upon said rod, as shown in fig. 1. Upon the opposite end of the rod a another cone c is put, with its apex directed inward toward the apex of its opposite cone. A set-screw, S, is then applied to the rod a, and screwed up tightly, thus confining the rod a in place in the centre of the hub. It will be seen that the two cones will adjust themselves, (while the screw S is being tightened,) to the ends of the hub, and bring the axis of the rod a to exactly coincide with the axis of a bore, A', through the hub, which bore should be in the centre of the hub. Upon the enlarged shoulder a' a staff, n, is slipped, which is perpendicular to the rod a, and which is kept in place but allowed to turn around its rod a by means of a thumb-nut and a washer applied on the screw-threaded end of said rod, as shown in figs. 1 and 2. The staff n is a straight piece, of any suitable length, having a hole bored in its upper end in a direction with its length, for receiving a pin, e, through which a number of holes are made transversely corresponding to holes which are made transversely through the staff, as shown in figs. 2 and 3. At the inner end of the pin e a wedge-key, r, is passed through a hole which is made transversely through the staff, so that said key will act upon and press outward the pin e, and thus rigidly secure in place a transverse gauge-rod, t, which is passed through the holes made through the staff n and pin e, as shown in fig. 2. After centring and confining the pivot-rod a to the hub, which is done by screwing up the nut S on the inner end of the hub, it is only necessary to adjust the gauge-pin t in a proper position, and secure it in place by pressing in the key r. When one spoke is adjusted to the proper dish, and the gauge-pin brought up to it and secured to its staff as aforesaid, the other spokes are all set at the same dish by the gauge-pin.

Having described my invention, what I claim as new, and desire to secure by Letters Patent, is—

The combination of perforated rod *e* and key *r*, with the staff *n*, and its gauge-pin *t*, substantially in the manner and for the purposes described. FRANCIS J. WEBER.

FRANCIS J. WEBER.
